UNITED STATES PATENT OFFICE

160,862

AUTOMATIC SHEET FEEDING APPARATUS

Elmer L. Johnson, Chicago, Ill., assignor to Bell & Howell Company, Chicago, Ill., a corporation of Illinois

Application June 18, 1949, Serial No. 3,402

Term of patent 14 years

(Cl. D64—11)

To all whom it may concern:

Be it known that I, Elmer L. Johnson, a citizen of the United States, residing at Chicago, State of Illinois, have invented a new, original, and ornamental Design for an Automatic Sheet Feeding Apparatus, of which the following is a specification, reference being had to the accompanying drawing, forming a part hereof.

In the said drawing—

Figure 1 is a front perspective view of an automatic sheet feeding apparatus, showing my new design; and

Figure 2 is rear perspective view of the same.

I claim:

The ornamental design for an automatic sheet feeding apparatus, as shown.

ELMER L. JOHNSON.
